UNITED STATES PATENT OFFICE.

STEAVEN A. CARTER, OF ARGENTA, ARKANSAS.

SMOKING-PIPE.

1,245,316.

Specification of Letters Patent.

Patented Nov. 6, 1917.

Application filed July 19, 1916. Serial No. 110,062.

To all whom it may concern:

Be it known that I, STEAVEN A. CARTER, a citizen of the United States, and a resident of the city of Argenta, county of Pulaski, 5 and State of Arkansas, have invented certain new and useful Improvements in Smoking-Pipes, of which the following is a specification.

My invention relates to improvements in 10 smoking pipes, and has for its object the production of a pipe of this character which will be adapted to afford a cool and pleasant smoke to the user.

A further object is the production of a 15 smoking pipe which will be of simple and economical construction.

Other objects will appear hereinafter.

With these objects in view, the invention consists in the combinations and arrangements of parts hereinafter described and 20 claimed.

The invention will be best understood by reference to the accompanying drawings forming a part of this specification, and in 25 which,

Figure 1 is a central section of a pipe embodying the invention,

Fig. 2 is a top plan view thereof, and

Fig. 3 is a section taken on line $\alpha-\alpha$ of 30 Fig. 1.

The preferred form of construction, as illustrated in the drawings, comprises a bowl 1 from the lower portion of which leads a tubular stem 2 of conventional construction. The bottom of the bowl 1 is provided with a removable closure 3 and secured in said bowl, intermediate the ends thereof, is a foraminated false bottom 4 preferably of wire mesh.

Arranged below the member 4 is an angular partition 5 consisting of a central longitudinally extending portion and a transversely extending portion, the latter being adapted to close off one-half of the 45 lower portion of the bowl, as will be readily understood. Formed in the lower edge of the vertically extending portion of the partition is a plurality of notches or openings 6 through which the smoke is adapted to 50 pass from one side of said portion of said

partition to the other. The arrangement is such that the stem 2 communicates with the portion of the bowl which is closed off by the transversely extending portion of the partition, as seen.

With this arrangement, it will be seen, 55 that a tortuous smoke passage is formed in the lower portion of the bowl, the course of the smoke being downwardly at the open side of the partition, thence through the opening 6 to the other side of the partition, and thence upwardly and out through the passage in stem 2. Arranged in the tortuous passage thus formed are pieces of cotton or other suitable absorbent material 7 which 60 are adapted to collect nicotine or other impurities with which the smoke is laden, so as to insure a cool, mild smoke in the use of the pipe. When desired, the pieces of absorbent material may be removed, and replaced with fresh ones by simply removing the closure 3.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations 75 and modifications as come within the scope of the appended claim.

Having described my invention what I claim as new and desire to secure by Letters Patent is:

A smoking pipe comprising a bowl; a tubular stem leading from said bowl; an angular partition in said bowl forming a tortuous smoke passage in the lower portion of said bowl, said partition consisting 80 of a central longitudinally extending portion and a transversely extending upper end portion closing off one side of the lower portion of said bowl, the lower edge of said longitudinally extending portion of said 85 partition being provided with an opening, said stem communicating with the lower portion of said bowl at the side thereof closed by said transversely extending portion of said partition; an absorbent element 90

arranged in said passage; a removable closure at the bottom of said bowl through which said absorbent element may be removed; and a foraminated false bottom in
5 said bowl above said partition, substantially as described.

In testimony whereof I have signed my

name to this specification in the presence of two subscribing witnesses.

STEAVEN A. CARTER.
